(57) **CLAIM**

The ornamental design for a measuring spoon, as shown and described.

DESCRIPTION

FIG. 1 is a left side elevational view of a measuring spoon showing my new design, the right side being a mirror image thereof;

FIG. 2 is a perspective view thereof as seen from the upper left;

FIG. 3 is a top plan view thereof;

FIG. 4 is a perspective view thereof as seen from the lower left side;

FIG. 5 is a bottom view thereof;

FIG. 6 is a perspective view thereof as seen from the upper right side; and,

FIG. 7 is a perspective view thereof as seen from the lower right side.
